UNITED STATES PATENT OFFICE.

JOHN D. BILLINGS, OF NEW YORK; N. Y., ASSIGNOR OF ONE-HALF TO
CHARLES WHITE, OF SAME PLACE.

HORSESHOE.

SPECIFICATION forming part of Letters Patent No. 283,850, dated August 28, 1883.

Application filed March 12, 1883. (No model.)

To all whom it may concern:

Be it known that I, JOHN D. BILLINGS, a citizen of the United States of America, residing at New York, in the county of New York and State of New York, have invented certain new and useful Improvements in Horseshoes, of which the following is a specification.

The invention consists of a horseshoe constructed with a continuous calk extending from heel to heel, said calk being beveled on its inner face at the toe and tapered thence toward the heels, said shoe being provided with a continuous grooved flange extending from heel to heel outside the calk, and with inner flanges extending from points near the toe to the heels. A shoe thus constructed is adapted to receive the fastening-nails at any point, to wear evenly on its face, and avoids a dead blow at the heels.

In the drawings, Figure 1 is a perspective view of a bar from which this improved shoe is formed by the operation of bending. Fig. 2 is a perspective view of this improved shoe from the under side. Fig. 3 is a longitudinal section through the toe of the shoe. Fig. 4 is a transverse section through one of the quarters on line 4 4 of Fig. 3. Fig. 5 is a transverse section through the toe on line 5 5 of Fig. 3.

In the drawings, A represents the platform or body of the shoe, which is of uniform width

from end to end. The continuous calk B projects downward from the center of the under side of said platform and extends from end to end thereof. At the middle of the bar and front of the shoe the calk is beveled from its lower face to the edge of the platform, and is tapered from the points *a a* on either side toward the heels. That part of the platform which is outside the calk constitutes an angular or grooved flange, A', through which the nails are passed to fasten the shoe upon the foot. The inner flanges, A²A², which extend from the points *a a* to the heels, serve to impart vibration to the shoe and avoid the dead-stroke, which tends to make the foot sore. The beveled and tapered portion at the front of the shoe sustains the greater friction at that point, causing the shoe to wear even.

What is claimed as the invention is—

A horseshoe consisting of a platform provided with a central continuous calk extending from heel to heel, said calk being beveled at the toe and tapered thence toward the heels, said shoe having a continuous angular or grooved flange extending from heel to heel outside the calk, and inner flanges extending from points near the toe to the heels, substantially as described.

JOHN D. BILLINGS.
